UNITED STATES PATENT OFFICE.

WILLIAM E. BISHOP, OF KANSAS CITY, KANSAS.

STAMPING MACHINE.

1,416,442.

Specification of Letters Patent. Patented May 16, 1922.

Application filed October 27, 1919. Serial No. 333,608.

To all whom it may concern:

Be it known that I, WILLIAM E. BISHOP, a citizen of the United States, residing at Kansas City, in the county of Wyandotte 5 and State of Kansas, have invented certain new and useful Improvements in Stamping Machines, of which the following is a specification.

My invention relates to a machine for 10 stamping or printing words, symbols, or other distinctive marks on articles of food such as nuts, oranges, lemons, etc., and in its present form embodies a hopper for holding the articles, dies for printing the articles, 15 chutes for directing the articles from the hopper to the dies, means for presenting the articles one by one to the dies to insure the stamping of each article, and means to prevent the articles from clogging between the 20 hopper and the chutes.

In the accompanying drawings which disclose the preferred embodiment of the invention:

Fig. 1 is an end elevation of the machine.

Fig. 2 is a broken plan view of the machine.

Fig. 3 is a broken vertical cross section taken on line III—III of Fig. 2.

Fig. 4 is a broken horizontal section, enlarged, on line IV—IV of Fig. 7, of the stamping mechanism and associated parts.

Fig. 5 is a detail perspective view of the dies for printing or stamping the articles.

Fig. 6 is a detail perspective view of a 35 reciprocatory stop to support the articles in position to be stamped or printed.

Fig. 7 is a broken side elevation, partly in section, of the stamping mechanism and associated parts.

Fig. 8 is a horizontal section on line 40 VIII—VIII of Fig. 7.

Fig. 9 is an irregular vertical longitudinal section on line IX—IX of Fig. 8.

Fig. 10 is a cross section, enlarged, on line 45 X—X of Fig. 7.

Fig. 11 is a fragmentary section of an agitator.

In carrying out the invention, I employ a suitable table 2, consisting in the present 50 instance of a horizontal top 4 and supporting legs 6.

8 designates a hopper in which the articles to be stamped are placed. Said hopper 8 is carried above the table 2 on suitable 55 means, such as brackets 10 secured upon two oppositely-disposed, inclined supporting

members 12 supported by brackets 14 and 16 resting upon the table top 4 and the top of a frame 18, respectively. As disclosed on Figs. 1 and 3, the frame 18 rests upon the 60 table top 4.

22 designates rows of chutes leading from opposite sides of the hopper bottom to deliver the articles to the stamping or printing batteries 24 on opposite sides of the 65 table top 4.

The chutes 22 are open at that portion of their undersides which extend over a reciprocatory agitator 26, which moves forward and backward to prevent the articles from 70 becoming clogged in the bottom of the hopper 8 and at the entrance to the chutes 22.

The upper surface of the agitator 26 is corrugated as disclosed more clearly on Figs. 2 and 11, to better engage and move the 75 articles to and fro, and slopes in both directions from a central point to cause the articles to roll down the chutes 22. The agitator 26 is mounted on antifriction rollers 28

and ball-bearings 30 arranged to traverse 80 rails 32 and ball races 34, respectively, fixed upon the upper portion of the frame 18.

Reciprocatory motion is imparted to the agitator 26 by suitable means such as an eccentric 36, the rod 38 of which is pivotally 85 connected at its forward end to a bifurcated lug 40, fixed to the adjacent end of said agitator 26. The disk of the eccentric 36 is fixedly-mounted upon a shaft 42 journaled in

bearings 44 and 46 driven by suitable means, 90 such as a bevel gear 48 intermeshing with a bevel gear 50. The bevel gear 50 is driven from a suitable motor 52 through a train 54. The motor 52 is, preferably, supported in a hanger 56 depending from the underside of 95 the table top 4.

Referring now more particularly to the stamping batteries 24 arranged at the lower ends of the chutes 22 and disclosed more clearly on Figs. 4 to 10, inclusive, each consists of a casing 58 fixed on top of the table 4 and reinforced at its sides with longitudinal plates 60, provided with upper and lower slideways 62 and 64, respectively. The 100 slideways 62 support a reciprocatory stop 66 provided with a stem 68, extending rearwardly through a cross-head 70 slidably mounted in slots 72 and 74 extending longitudinally of the casing 58 and the plates 60, respectively. An expansion spring 76 is interposed between the rear end of the stop 66 and the cross head 70 to yieldably hold said

105
110

stop a predetermined distance in advance of said cross-head, which is held on the stem 68 by suitable means such as a transverse pin 78.

- 5 80 designates a second reciprocatory stop provided with a body portion 82 having longitudinal grooves 84 to receive the slideways 64 upon which said body portion 82 is reciprocably mounted. The body portion 82
 10 has a pair of internal longitudinal slideways 86 upon which a stamping die 88 is reciprocably mounted, said stamping die being provided at its sides with longitudinal grooves 90 to receive the slideways 86.
 15 The reciprocatory stops 66 and 80 are alternately moved forwardly and backwardly through the upper and lower portions, respectively, of a port 92 in one of the brackets 14 leading from the discharge end
 20 of the registering chute 22 to an underlying port 94 in the table top 4. Suitable means such as levers 96 are employed to actuate the stops 66 and 80. Said levers 96 are fulcrumed on pivots 98 at opposite sides of the
 25 casing 58 and pivotally connected at their upper ends to the cross-head 70 by links 100. The lower ends of the levers 96 are connected to opposite sides of the stop 80 by pin-and-slot connections 102. The sides of
 30 the casing 58 and the plates 60, have longitudinal slots 106 through which the pins 102 extend.

The die 88 is provided at its forward end with any suitable symbol, letters, or mark, such for instance as that disclosed at 108 on Fig. 5, and is supplied with ink from a pad 110, which in turn is supplied from an ink well 114 threaded into a frame 116 carrying the pad 110. Access is had to the ink well 114 to supply the same with ink, through a longitudinal slot 117 in the stop 66 and an opening 118 in the top of the casing 58.

The ink pad frame 116 is mounted upon a pivot 120 extending transversely through the sides of the casing 58 and the plates 60 and provided with a coil spring 122, one end of which is secured to said pivot 120 and the other to the frame 116 for the purpose of swinging the same downwardly to 50 the position disclosed on Fig. 9, to ink the symbol 108 on the face of the die 88. When the die 88 moves forwardly to stamp an article it pushes the pad 110 and its frame 116 upwardly to the position disclosed on 55 Fig. 7, where it is held by the upper surface of the body portion 82 of the reciprocatory stop 80 and a pair of arms 124 bearing on top of said stop 80 and fixed to the pad frame 116.

60 The rear end of the die 88 is provided with a stem 126 extending loosely through a plate 128 secured to the rear end of the body portion 82 of the stop 80. A coil spring 130, embracing the stem 126 and interposed between the rear end of the die

88 and the plate 128, yieldably holds the die a predetermined distance in advance of the plate 128, such distance being determined by a pin 134 extending transversely through the rear end of the pin 126 and bearing against the rear side of the plate 128.

The stop 80 is actuated by an eccentric 136, the rod 138 of which is pivotally connected to the rear side of the plate 128. 75

The eccentrics 136 are fixedly mounted upon shafts 140 carried at opposite sides of the table 2, by brackets 142 and provided with fixedly mounted pulleys 144 driven by belts 148 running around pulleys 150 driven by the train 54. 80

In practice the hopper 8 is filled with articles to be stamped, after which the motor 52 is started to actuate the working mechanism through the intermediacy of their various 85 connections above-described. As the agitator 26 moves to and fro it causes the articles to pass into the chutes 22 which conduct the articles to the ports 92, each of which is only large enough to admit one article at a 90 time. Should the stops 66 happen to be in forward position as the initial articles are about to enter the ports 92, said articles are arrested by said stops 66 until the same move backwardly, while the stops 80 move 95 forwardly to intercept the articles when they are permitted to enter the ports 92, on the backward movement of the stops 66. As the stops 80 move forwardly to intercept the articles, the dies 88 are carried therewith 100 and on contacting the articles, stamp the same, after which the stops 80 and the dies 88 move backwardly and uncover the ports 94 to permit the articles to fall therethrough.

As the dies 88 move forwardly to stamp the articles as above described, they swing the pads 112 upwardly against the action of the springs 122, by which time the stops 80 pass beneath the arms 124 and hold the same and the pads 112 in raised position until the 110 stops 80 and the dies 88 move backwardly to the position disclosed on Fig. 9. Thus it will be understood that the face or printing end of the dies will be supplied with fresh ink for each printing operation. 115

By having the stops 66 and 82 alternately move forwardly as above described, it will be impossible for articles to pass through the ports 92 without being stamped, and owing to the yielding connection afforded by 120 the springs 76 and 130, said stops are permitted to yield in case articles should become lodged between the forward ends of said stops and the opposite sides of the ports 92, thereby avoiding damage either to the 125 stops or the articles. Owing to the yielding connection between the dies 88 and the stops 80, the forward movement of said dies may be greater or less according to size of the articles to be stamped.

From the foregoing description it is apparent that I have produced a machine of large capacity and embodying the advantages above enumerated, and while I have shown and described the preferred form of my invention, I reserve the right to make such changes in the construction, proportion and arrangement of parts as properly fall within the spirit and scope of the claims.

10 Having thus described my invention, what I claim and desire to secure by Letters Patent, is:

1. In a machine of the character described, a receptacle for articles to be stamped, mechanism for stamping the articles, inclined means for conducting the articles from the receptacle to said stamping mechanism and having openings in their bottom portions, a reciprocatory agitator underlying the open 20 portions of the bottoms to prevent the articles from clogging, and means for presenting the articles to the stamping mechanism.

2. In a machine of the character described, a receptacle for articles to be stamped, mechanism for stamping the articles, means for conducting the articles from the receptacle to said stamping mechanism, a reciprocatory agitator arranged horizontally beneath the conducting means to prevent the articles from becoming clogged between said receptacle and the conducting means, and anti-frictional supporting means for said agitator.

3. In a machine of the character described, a receptacle for articles to be stamped, mechanism for stamping the articles, means for conducting the articles from the receptacle to said stamping mechanism, a stop operably mounted to regulate the passage 40 of the articles to the stamping mechanism, a stop operably-mounted to support the articles in position to be stamped, and means for alternately moving said stops to active position.

45 4. In a machine of the character described, means for stamping articles, and a stop

carrying said stamping means and arranged to support the articles in position to be stamped.

5. In a machine of the character described, 50 means for stamping articles, a stop carrying said stamping means and arranged to support the articles in position to be stamped, and means for moving said stop to active and inactive positions. 55

6. In a machine of the character described, means for stamping articles, a stop carrying said stamping means and arranged to support the articles in position to be stamped, means for moving said stop to active and 60 inactive positions, and yielding means interposed between the stamping means and the stop whereby the latter may continue its movement to active position after the stamping means is arrested by an article to be 65 stamped.

7. In a machine of the character described, means for stamping articles, a stop carrying said stamping means and arranged to support the articles in position to be stamped, 70 means for moving said stop to active and inactive positions, inking means arranged to ink the stamping means when the same is in inactive position, and means on said inking means to ride on the stop and hold 75 the inking means out of the path of the stamping means.

8. In a machine of the character described, a movable die for stamping articles, a pad for inking said die, a swingable frame carrying said pad, resilient means engaging said frame to hold the pad against the die, means movable with the die to engage the frame and cause the same to carry the pad away from the die, and mechanism for presenting 85 the articles to the die for stamping.

In testimony whereof I affix my signature in the presence of two witnesses.

WILLIAM E. BISHOP.
